COIN SLIDE FOR VENDING MACHINES OR THE LIKE

Harry Greenwald, New York, N.Y., assignor of one-third
each to Louis Wolff and Harry Silbergelait

Filed Nov. 18, 1964, Ser. No. 82,674

Term of patent 14 years

(Cl. D52—3)

FIG. 1 is a front elevational view of a coin slide for vending machines or the like showing my new design;

FIG. 2 is a side elevational view thereof;

FIG. 3 is a top plan view thereof;

FIG. 4 is a bottom plan view thereof; and

FIG. 5 is a fragmentary cross sectional view taken on line 5—5 of FIG. 1.

The dominant features of my design reside in the portions shown in full lines.

I claim:

The ornamental design for a coin slide for vending machines or the like, substantially as shown, and described.
